CONTINUOUS BEATER SYSTEM

Paul B. Lacy, Covington, Va., assignor to West
Virginia Pulp and Paper Company, New York,
N. Y., a corporation of Delaware

Application June 28, 1929, Serial No. 374,458

24 Claims. (Cl. 92—20)

This invention relates to paper manufacture and more particularly to an improvement in the process and apparatus for preparing the pulp fibres for the paper-making machines and for 5 systematically mixing the various ingredients which may enter into the sheet of paper.

The practice in paper-making has been to pump the pulp stock intermittently from the storage chest into beaters, or Hollanders, where the sizing and coloring materials are added, and continue the beating process until the batch of fibre is reduced to the desired state of disintegration. In following this practice, the beating is accomplished by means of revolving rolls carrying bars 10 or knives which coat with the bars or knives of a bed plate to break up the fibrous material passing therebetween. When each batch is completed the beaten material is dumped into the beater chest by gravity, from which it may be pumped to the paper-making or Fourdrinier machines, where the water is separated from the fibres. Repeated efforts have been made to provide for the continuous operation of such beaters, by using perforated back falls and other means 15 for withdrawing the disintegrated material, but these have not proven commercially successful.

It is an object of my invention to provide a continuous process and improved means for beating the pulp. It is a further object to provide a 20 method for accurately controlling the consistency of the pulp liquor entering the beaters and for utilizing the white or back water and reclaimed stock from the save-all. Another object is to provide an improved method for incorporating 25 clay, coloring material, sizing and alum into the stock, and an improvement in the control of these ingredients. A further object is to avoid the cutting action of the beaters ordinarily used. Other objects and advantages will become apparent.

In describing my invention, reference will be made to the drawings, in which:

Figure 1 is a diagrammatic view indicating the several steps of my improved process.

Figure 2 is a front elevation of my improved beater.

Figure 3 is a sectional view, taken on line 3—3 of Figure 2, and

Figure 4 is a sectional view, taken on line 4—4 of Figure 3.

In the preferred application of my invention, pulp stock, which has been treated by the sulphite, soda, or some other suitable process, and having a consistency of about 2 to 5% fibres, is 55 pumped from the storage chest (1) to a con-

sistency regulating box (2) and from there into a thickener (3) of standard construction. The thickener is operated to remove sufficient water to produce a stock of considerably higher concentration than that desired in the beaters, for 60 example, one having a concentration greater than 8% of fibre and preferably from 8 to 30% fibre. This thickened stock is then passed through a regulator (4) where white or back water, and/or reclaimed stock, from the paper machines, and 65 additional fresh water, if necessary, are added to dilute the stock to the consistency of about 3 to 5% fibre. This consistency should be such that when the clay, color, alum and sizing have been added the stock will still be more concentrated than the minimum concentration permissible in the material fed to the paper-making machines.

Suitable quantities of clay, coloring material and alum are added as the stock passes to the 75 beater tub (5). If these ingredients are added as liquids they may be accurately measured through a microscopically adjusted V-notch weir. If it is preferred to add the alum, or other ingredients, in a dry form, they may be supplied 80 through suitable standard dry-feed apparatus. The proper amount of alum may be determined from the pH-value, which may be indicated by a continuously recording hydrogen-ion indicator.

The stock is then pumped into the beater tub 85 (5) and after passing through the beater tub is pumped through the inspection box (6), where the stock is automatically and accurately diluted to the concentration desired at this stage of the paper-making process. The stock may then be 90 pumped to the beater chest (7), from which it may be withdrawn as needed.

The beater tubs are shown in detail in Figures 2 to 4. These figures show a wooden container (5) divided into three sections by wooden partitions (8) and (9). Within each of these sections a cylindrical beater drum (10), (10a) or (10b) is fixed to a shaft (11), which passes through stuffing boxes in the ends of the wooden tub and is rotated by a suitable source of power (not shown), 95 through a gear (12). Each of the drums (10), (10a) and (10b) has a perforated cylindrical surface and is open at each end. The perforations in the drum (10) are preferably about two inches in diameter, while those in the other two drums 100 should be about one and one-half inches in diameter. The drums are of sufficient length to nearly contact with the wooden ends of the tub, leaving spaces therebetween which should be sufficiently small to prevent the passage of a substantial quan- 110

tity of the fibres. The bottom of each section is curved to follow the circumference of the drum supported therein and scraping plates (13), may be fixed to the outer surface of each of the drums 5 at spaced points and parallel to the axis of the cylinder. If desired, the scraping plate may extend around the drum in the form of a spiral.

An inlet pipe (14) enters one side of the first section of the beater tub above the upper surface 10 of the drum (10). An outlet pipe (15) is connected to an end of this section of the beater tub at a point opposite the lower portion of the inner surface of the drum (10). This outlet leads to a centrifugal pump (16), the outlet side of which 15 is connected to a bifurcated pipe having a branch (17) entering the first section of the beater tub above the drum (10) and a branch (18) entering the second section of the beater tub above the cylinder (10a). The flow of liquid in the branches 20 of this outlet pipe may be controlled by the valves (19) and (20). Similar pipes (15a), (15b), (17a), (17b), (18a) and (18b) connect the second and third sections of the beater tub with centrifugal pumps (16a) and (16b). The control of liquid 25 from the last-mentioned centrifugal pumps may be regulated by valves (19a) and (19b), (20a) and (20b). The branch (18b) of the outlet pipe from the centrifugal pump (16b) is connected to the automatic consistency regulator (6) having an 30 outlet (21) by which the beaten stock may be conveyed to the beater chest (7).

In operating the beaters, the perforated drums (10), (10a) and (10b) are rotated at a speed of about ten revolutions per minute and the stock 35 from the regulator (4) is conveyed continuously into the first section of the beater tub by the pipe (14). This stock will splash upon the exposed perforated cylindrical surface of the rotating drum (10) and the fibres will be drawn, with the 40 liquid, through the perforations in the drum (10) and through the outlet pipe (15), by the centrifugal pump (16).

From the pump (16) the stock is forced through the branch (18) of the outlet pipe, to be splashed 45 upon the exposed surface of the rotating perforated drum (10a) having somewhat smaller perforations. From this section it is pumped by a similar pump (16a) and pipes (15a) and (18a) to be splashed upon the perforated surface of 50 the rotating drum (10b) in the third section.

By means of the valves (19), (19a) and (19b), in the branches (17), (17a) and (17b) of the outlet pipes from the centrifugal pumps, a portion, or all, of the stock may be bypassed to be recirculated and splashed upon the rotating drum in 55 the section from which it has been withdrawn.

The level of the liquid in each section of the beater tub is maintained at a height of about two-thirds the diameter of the cylindrical drum, by 60 regulating the inlet and outlet supply. The fibres will be disintegrated and opened up by the splashing action upon the perforated drum surface, by being drawn through the perforations in the cylindrical surface, and by the beating action of the 65 vanes of the centrifugal pump.

By the time the stock containing the clay, coloring material and alum have reached the second section of the beater tub, the agitation will have completely distributed these materials through the 70 remainder of the stock. At this point a measured quantity of sizing material, such as rosin soap, may be added by means of a spray pipe connected to a microscopically adjusted V-notched weir.

Since the pH. value throughout the solution will 75 have been made constant by the agitation, the

spraying of the rosin soap into the second beater will result in the uniform deposition upon the fibres, of the rosin liberated by the reaction between the aluminum sulphate and rosin soap. A further advantage gained by following this procedure results from the complete distribution of the color and clay before the sizing is deposited, thereby permitting a uniform distribution of color and filler throughout the fibres before they become coated with sizing.

80
85

The recirculation of the pulp stock in each section of the beater tub may be regulated, by controlling the amount of stock being bypassed, to obtain the desired degree of agitation and disintegration. When this is accomplished, the disintegrated stock from the last section of the beater tub may be conveyed through the branch pipe (18b) to the automatic consistency regulator (6), where sufficient water is added to bring the dilution up to that required at this stage of the paper-making process, preferably to a concentration of 3 to 4% consistency.

90
95

It is not new to thicken stock to slightly above the concentration required in pulp beaters and add a small quantity of water in the regulator. 100 My process, however, includes the step of thickening to substantially above the concentration required in the pulp beater whereby all of the white or back water may be added at this point.

100

By the term back-water, as used in the description and claims, I mean the water which separates from the paper-making material when the paper-making material is deposited on the Fourdrinier wire. In other words, the water, passing through the wire, which water contains 110 filler, short fibres, coloring material, alum, sizing etc.

105

By my procedure I provide for the addition of this white or back water at a point where the coloring material, alum, clay and sizing contained therein may be thoroughly agitated with the stock in the beaters and thereby used to the best advantage. By using this high degree of concentration in my process, all of the white or back water can be added without any separation thereby avoiding the loss occasioned by discarding this material or by separating it for use with stock of lower concentration.

115
120

Since the standard consistency regulators will only act to dilute the stock, it is important that 125 the consistency of the stock, after it leaves the thickeners, be maintained at all times, up to the time for diluting the stock in the consistency regulators, at a concentration higher than the minimum concentration permissible in the paper-making machines. By my process of thickening to substantially above the optimum concentration in the beaters, I provide not only for the economical utilization of valuable waste products, but also for the accurate control of the 130 ingredients added to the stock, to produce a uniformly high quality of paper.

130

In my preferred operation, the process is continuous and one of its advantages lies in its avoidance of the delays attendant upon an intermittent or batch process.

135
140

I am also aware that rotating cylinders have been used for filtering and separating solid materials and paper stock. My process is not one of separation, however, but rather one of disintegration. The splashing action of the pulp upon the rotating perforated surfaces, and the contact with the metal while being drawn through the perforations, disintegrate and open up the fibre so that it may be suitable for use on the 145

140
145
150

- paper-making machines. The scrapers (13) attached to the rotating drum serve to agitate the stock and prevent settling of the fibres to the bottom of the tubs, and the blades of the centrifugal pumps cause further agitation of the pulp, and further disintegration and opening of the fibres. 5
- The construction of the beater tubs and drums may be altered and other means for splashing the pulp upon or drawing it through the perforated surfaces may be used. It is also apparent that many modifications in the means for scraping and for agitation or circulation of the stock may be used. 10
- 15 By using my method and apparatus for disintegrating and opening the fibres, I avoid the cutting of the fibres which occurs between the bars and bed plate of the beaters or Hollanders in common use. My process has the further advantage of cleanliness, for the apparatus is entirely enclosed during the beating operation and there is no opportunity for dirt to be mixed with the stock during this operation.
- In describing my invention, I have included 25 references to a preferred procedure and have made specific references to certain details, such as the rate of rotation of the perforated drum and the size of the perforations in the drum, and certain ingredients to be added. These terms 30 have been used for the purpose of illustrating the operation and are not intended to be interpreted as limiting it. It is apparent, for example, that other and more or less ingredients 35 may be mixed with the paper pulp, depending upon the particular type of paper being produced. It is also apparent that many other modifications and applications of my invention may be made and it is not intended to hereby limit its scope to the particular embodiments described.
- 40 What I claim is:
1. A method for disintegrating paper pulp comprising splashing the pulp stock upon an exposed surface of a perforated drum while rotating the latter, and drawing the excess stock through perforations in the rotating drum. 45
  2. A method for disintegrating paper pulp comprising splashing the pulp stock upon an exposed surface of a perforated drum while rotating the latter, drawing the excess stock through perforations in the drum and bypassing a portion of the stock for recirculation in the same manner. 50
  3. A continuous method for disintegrating paper pulp comprising splashing pulp stock upon an exposed surface of one of a plurality of perforated drums while rotating the latter and impelling the stock to draw it successively through perforations in each of the said drums and to splash it successively upon the exposed perforated surfaces of each of the remaining drums. 55
  - 60 4. A method for disintegrating paper pulp comprising splashing pulp stock upon an exposed surface of one of a plurality of perforated drums while rotating the latter, impelling the stock to draw it successively through the perforations in each of the said drums and to splash it successively upon the exposed surfaces of each of the remaining drums.
  - 65 5. In the preparation of paper pulp for the paper-making machines, the steps comprising thickening all of the pulp stock to a concentration of fibre of greater than 8 percent, adding substantially all the white or back-water to dilute it to a concentration slightly above that desired in the 70
  - paper-making machines, beating the diluted stock to disintegrate the fibre and diluting it to the concentration desired in the paper-making machines. 75
  6. In the preparation of paper pulp for the paper-making machines, the steps comprising thickening the pulp stock to a concentration considerably greater than that desired in the beating operation, adding white or back-water to dilute it to a concentration slightly above that desired in the paper-making machines, splashing the diluted stock upon an exposed surface of a perforated drum while rotating the latter, drawing the stock through perforations in the drum, bypassing a portion of said stock to recirculate it through the perforated drum, and further diluting the stock from the beater to the concentration desired in the beater chest. 80
  7. In the preparation of paper pulp for the paper-making machines, the steps comprising thickening the pulp stock to a concentration considerably greater than that desired in the beating operation, adding white or back-water to dilute it to a concentration slightly above that desired in the paper-making machines, splashing the diluted stock upon an exposed surface of one of a series of perforated drums while rotating the latter, impelling the stock to draw it successively through perforations in each of the said drums and to splash it successively upon the exposed 85
  - 90
  - 95
  10. An apparatus for beating paper pulp comprising a tank, a rotatable perforated drum in said tank, means for splashing pulp stock upon an exposed surface of said perforated drum, and means for withdrawing pulp and liquid from the inner surface of said drum. 100
  - 110
  12. An apparatus for preparing paper pulp, comprising a thickener for increasing the concentration 105
  - 115
  - 120
  - 125
  - 130
  - 135
  - 140
  - 145
  - 150

- centration of the fibre in the pulp stock, means for diluting the thickened pulp stock with waste water from the paper machines as the pulp stock passes to a tank containing a perforated rotating 5 drum positioned so that the pulp will splash upon an exposed surface of the drum, and means for withdrawing the pulp and liquid from the interior of the rotating drum.
13. An apparatus for beating paper pulp, comprising a plurality of perforated drums rotating in separate compartments, means for spraying the pulp upon an exposed surface of the first drum, means for withdrawing the pulp and liquid from the interior of the first drum and spraying 10 it upon the exposed surface of a succeeding drum, means for adding alum to the pulp stock beaten in the first compartment, means for adding sizing to the pulp stock beaten in a subsequent compartment, and means for withdrawing the beaten 15 pulp stock from the interior of the perforated drum in the last compartment.
14. A method for disintegrating paper pulp comprising splashing pulp stock upon an exposed surface of a rotating foraminous cylindrical plate, drawing the excess pulp stock through perforations in the plate and thereafter passing the pulp 20 stock through a foraminous plate having perforations of smaller diameter.
15. A method for disintegrating paper pulp, comprising passing the pulp stock through a foraminous plate moving in the pulp stock and thereafter passing it through a second moving 25 foraminous plate containing perforations of smaller diameter.
- 30 16. In the preparation of paper pulp for the paper making machines, the steps comprising thickening the pulp stock to such concentration that all of the white water or back water may be added to it without diluting it to a concentration below that desired in the paper making machines, adding white or back water to dilute the thickened 35 pulp stock to a concentration slightly above that desired in the paper making machines, and beating the diluted stock to disintegrate the fibres.
- 40 17. In the preparation of paper pulp for paper making machines, the steps comprising thickening the pulp stock to such a concentration that all of the white or back water may be added to it without diluting it to a concentration below that 45 desired in the paper making machines, adding white or back water to dilute the thickened pulp stock to a concentration slightly above that desired in the paper making machines, continuously 50 passing the diluted stock through a perforated cylinder while rotating the latter and further diluting the stock to the desired concentration.
- 55 18. In the preparation of paper pulp for paper making machines, the steps comprising thickening the pulp stock to such a concentration that all of the white or back water may be added to it without diluting it to a concentration below that desired in the paper making machines, adding white or back water to dilute it to a concentration slightly above that desired in the paper making machines, adding measured quantities of clay, color and sizing while continuously passing the diluted stock through a perforated cylinder in rotation, and further diluting the stock to the concentration desired in the paper making machine.
- 60 19. An apparatus for beating paper pulp, comprising a tank, a perforated plate positioned within said tank and having a portion beneath the liquid level therein, and means for repeatedly drawing pulp and liquid through the perforations in said plate positioned beneath the liquid level.
- 65 20. An apparatus for beating paper pulp, comprising a tank, a plurality of perforated plates each having a portion positioned beneath the liquid level in said tank and means for drawing pulp stock successively through submerged perforations in each of such plates.
- 70 21. An apparatus for beating paper pulp, comprising a plurality of tanks, a movable perforated plate in each such tank having a portion positioned below the liquid level therein, means for drawing pulp and liquid through submerged perforations in each such plate and conveying it to the succeeding tank.
- 75 22. An apparatus for beating paper pulp, comprising a tank, a foraminous plate in said tank partially submerged beneath the liquid level therein, a second partially submerged foraminous plate having perforations of smaller diameter, and means for passing pulp stock through the first foraminous plate and thereafter passing it through the second foraminous plate.
- 80 23. An apparatus for disintegrating paper pulp, comprising a plurality of movable foraminous plates partially submerged beneath the pulp stock, and means for drawing the pulp stock through said foraminous plates in succession.
- 85 24. An apparatus for disintegrating paper pulp, comprising a tank, a cylindrical perforated plate rotatably mounted in said tank and having an open end inside of and adjacent a wall of said tank, means for supplying paper pulp to said tank, and a liquid outlet projecting through the wall of said tank at a point opposite the open end of said cylinder.

PAUL B. LACY. 130
